RAILROAD CAR TRUCK BOLSTER

Karl F. Nystrom, Nashotah, and Vernon L. Green, Milwaukee, Wis.

Application September 22, 1944, Serial No. 555,340

8 Claims. (Cl. 105—229)

Our invention relates to a fabricated truck bolster of the truss type wherein the respective elements or members are welded to each other to provide a composite unit of preformed sheet metal sections of predetermined configuration and arrangement, all integrally united to each other, and wherein the use of rivets is entirely eliminated.

Our improved bolster, which is somewhat similar to the old simplex type, is a material improvement thereof in a number of essential respects; as for example the angle of the tension member, with respect to the compression member, has been altered from approximately fifteen degrees to thirty degrees, thereby lowering the tension forces in proportion to the sine of the respective angles. Then too, with our improved bolster, the forces encountered by the side bearings, as well as the center plate load, have been provided for in an engineering manner by means of diverging or triangular struts or braces which may function as compression members on one side and as tension members on the other side depending on whether the load is on the center bearing or on a side bearing; the invention providing a truss type bolster wherein the tension loads are reduced.

With our invention a complete beam structure, regardless of the particular type of end plates or members employed, is provided, thus enabling any type of bolster ends to be applied in keeping with the spring and snubbing devices employed on the truck; and at the same time the use of end castings or forgings is eliminated.

The objects and advantages of our invention will be more fully comprehended from the following detailed description of the accompanying drawings wherein:

Figure 1 is a plan view of our improved truck bolster.

Figure 2 is a side elevation thereof.

Figure 3 is an enlarged longitudinal sectional view taken on the line 3—3 of Figure 1, viewed in the direction of the arrows.

Figure 4 is a vertical sectional view on the line 4—4 of Figure 3.

Figure 5 is a detail sectional view taken on the line 5—5 of Figure 3, looking in the direction of the arrows.

Our improved truss type truck bolster in the exemplification shown in the drawings consists of a top or compression member 10, preferably of channel form in cross-section, with comparatively wide side flanges 11, and at its transverse median line with an opening which is surrounded

on the lower side of member 10 by a depending king pin receiving tube 12 which preferably is welded to the compression member 10, as shown in Figure 3, and the top of member 10 about the central opening is provided with the annular center plate 13 which is welded to the top member. The bottom of tube 12 is provided with a king pin stop or pin 14 which may be welded to the end of tube 12 as shown.

10 The top or compression member 10, at predetermined distances removed from the center bearing plate, is provided with suitable side bearings 15, 15 which, in the specific exemplification are shown in the nature of rectangular boxes 15^a welded to the top member and provided with yieldable or wood filler blocks 16 provided with the metallic cap members 17. It will be understood that any suitable type of side bearing may be employed.

15 20 The top or compression member 10 extends substantially in a straight line from end to end and the ends are integrally united with the upwardly sloping ends of the tension member or bar 18; the ends of the compression member 10 25 and of the tension member 18 being welded to each other, as shown at 19 in Figure 3, with the tension member terminating in the plane of the compression member as more clearly shown in Figure 3.

20 30 The tension member 18 consists of a flat and comparatively thick strap or bar of predetermined length formed with a straight horizontal intermediate portion 18^a, disposed at a greater distance beneath the compression member than

35 35 has heretofore been the practice, with said portion 18^a made to extend beyond opposite sides of the center bearing portion of the compression member 10, where the ends of the tension bar are bent to provide the upwardly sloping portions

40 40 18^b whose ends are shown terminating adjacent to and in the plane of the upper surface of the compression member 10, with the ends of the compression member and of the tension member welded to each other, as indicated at 19.

45 The bolster at opposite sides of its transverse median line is provided with brace means whereby the bolster is reenforced at the load encountering points, namely at the center bearing and also at the side bearings as clearly shown in Figure 2. The straps or brace means as disclosed in the drawings, for the sake of easy forming, preferably consist of the V-shaped bars 20, with the bases or apex portions resting on the tension member at the junctures of the intermediate horizontal portion 18^a and the upwardly sloping per-

50 55

tions 18^b and secured thereto by welding, as indicated at 21, thereby firmly anchoring the brace members in place.

The diverging ends of the brace elements are intimately secured by welding, as indicated at 22, to the lower surface of the compression member 10, with one leg of each brace element secured beneath the center bearing member 13, in proximity to the king pin, receiving tube 12; while the other leg of each brace element is secured directly beneath the corresponding side bearing 15.

These brace bars are shown in the nature of flat bars substantially the same width as the tension member 18, see Figure 4; and each strut or brace element preferably is provided with a web 23 of sheet metal cut into triangular or V-shape form with its edges welded to the opposing faces of the V-shape strut members 20, preferably midway between the longitudinal edges thereof, as shown in dotted lines in Figure 1, and to the lower face of the compression member, as more clearly shown in Figure 3. The webs 23, for the sake of lightness, are each provided with a cut-out or hole 24; the webs act as stiffeners and prevent buckling of the strut bars when subjected to compression strains.

The structure described constitutes a complete trussed beam to which any type of end plates or members may be attached and in which the top or compression member is braced at the load bearing points by a pair of V-shaped struts which transmit the stresses or strains to the tension member at spaced apart points removed from the transverse median line of the tension member, namely at the junctures between the horizontal intermediate portion 18^a and the upwardly sloping end portions 18^b, disposed intermediate the vertical planes of the center bearing and the side bearings. The struts or brace members function both as compression members on one side and as tension members on the other side depending on whether the load is on the side bearing or on the center bearing; our improved bolster being designed to eliminate difficulties heretofore encountered, especially with the old simplex type which frequently became fractured or broken at the points subjected to side bearing loads. With our improved truss type bolster the tension forces are materially lowered in proportion to the sine of the respective angles at the junctures of the tension member with the compression member, resulting from the type of tension member employed and its greatly lowered position while still maintaining the required clearance therebeneath; namely a bolster whose top or compression member is free of undesirable bends and is substantially horizontal throughout its length; wherein proper distribution of the strains or stresses is obtained and the tension member provided with comparatively steep inclining end portions but without an undesirable sharp angle or bend in the intermediate portion thereof; the obtuse angles or bends in the intermediate portion of the tension member being braced by our improved V-shaped struts or brace members.

In the particular exemplification, the bolster is shown provided with end portions of somewhat box-form, which may be cast or formed of sheet metal as shown, provided with outer side walls 25, 25, bottom plate 26, top wall 27 and with inner side wall portions 28, 28. The top wall 27 is longitudinally slit intermediate its side edges and the partially severed or slit portion bent downwardly into contact with the bottom wall 26, and preferably welded thereto, as shown in Figure 3, to provide the inclining tension member

supporting ledge 29 which extends between inner walls 28, with the end of the tension member shown welded thereto, as shown in Figure 3. The top or web portion of the compression member 10, at opposite longitudinal sides is reduced or cut away to leave the extension 10^a at each end, which extends into the recess provided by the downwardly bent ledge forming portion 29, see Figures 1 and 3, and is welded to the tension member. The bottom wall 26 of each end portion is shown provided with bolster spring centering lugs or seats 30; and the outer side walls 25 are provided with laterally disposed guides 31 for slidably engaging the columns of the truck side frame.

In order to provide for either right or left application of the brake mechanism and to permit the connecting rod of said mechanism to be disposed at the top of the truck bolster, we show the compression or top member of the bolster, at opposite sides of the center bearing, provided with a pair of upwardly inclined lugs 32, apertured at their outer ends as shown in Figure 1; these lugs preferably being welded to the side flange of the top member.

The exemplification is believed to be the best embodiment of the invention, but structural modifications in certain respects may be possible without, however, departing from the spirit of our invention as defined in the appended claims.

What we claim is:

1. In a truss type truck bolster, the combination of a compression member extending in a horizontal plane from end to end, provided centrally with a center bearing and with side bearings in proximity to the ends; a tension member provided with an intermediate horizontal portion extending lengthwise to vertical planes intermediate the center bearing and each side bearing, with the ends bent upwardly at a steep inclination and brought into contact with the ends of the compression member at a comparatively high degree angle so as to lower the tension forces and welded thereto; and a pair of upwardly diverging brace members at opposite sides of the center of the bolster, with the lower ends of the brace members resting on and welded to the tension member at the ends of its horizontal portion, while the diverged upper ends of the brace members are welded to the compression member at points beneath the center bearing and the respective side bearing.

2. In a truss type truck bolster, the combination of a flanged sheet metal compression member provided centrally with a center bearing and with side bearings intermediate its ends and the center bearing; a tension member arranged beneath the compression member and provided with a horizontal portion extending to points intermediate the vertical planes of the center bearing and the respective side bearings with the ends inclined upwardly into angular contact with and welded to the ends of the compression member at a normally increased angularity whereby the tension forces are lowered; and a pair of brace members at opposite sides of the bolster center with the lower ends of the brace members resting on and welded to the tension member at the ends of its horizontal portion while the upper ends are welded to the bottom of the compression member in proximity to the center of the bearing and to points beneath the respective side bearings.

3. In a truss type truck bolster, the combination of a compression member extending in a horizontal plane from end to end provided with a center bearing and with side bearings in proximity to its ends; a tension member arranged be-

neath the compression member and provided with end portions inclining upwardly into contact with the ends of the compression member at an angularity in excess of fifteen degrees, with the ends of the tension member and of the compression member welded together; and a pair of V-shaped brace members whose diverging upper ends are secured to the bottom of the compression member beneath the respective side bearings and beneath the center bearing while the lower ends of the brace members are secured to the tension member at points intermediate the vertical planes of the center bearing and the respective side bearings.

4. In a fabricated truss type truck bolster, the combination of a flanged sheet metal top or compression member provided with a center bearing and with side bearings intermediate the center bearing and the ends of the compression member; a tension bar, spaced beneath the compression member, provided with an intermediate horizontal portion and straight upwardly inclining end portions terminating at the ends of the compression member and welded thereto; and a pair of V-shaped brace members intermediate the compression member and the tension bar and the apex of each brace member welded to the tension member at the respective end of its horizontal portion while the diverging upper ends are welded to the bottom of the compression member beneath the center bearing and the respective side bearing, said brace members being provided with reinforcing webs welded intermediate the upwardly diverging ends.

5. In a truss type truck bolster, the combination of a flanged sheet metal top compression member, extending horizontally from end to end, provided centrally with an opening; a king-pin receiving tube welded to the bottom of the compression member about said opening; a center bearing member welded to the top of the compression member about said opening; side bearings welded to the top of the compression member intermediate the center bearing member and the ends of the compression member; a tension bar, spaced beneath the compression member, provided with an intermediate horizontal position and straight upwardly inclining end portions terminating at the ends of the compression member intermediate the flanged sides and welded thereto; end portions welded to the flanged sides at the ends of the compression member and provided with declining tension member supporting portions welded to the ends of the tension member; and a pair of upwardly diverging brace members welded to the tension member and to the bottom of the compression member beneath the center bearing member adjacent the king-pin receiving tube and beneath the respective side bearings.

6. In a fabricated truss type truck bolster, the combination of a sheet metal top compression member, extending horizontally from end to end,

provided centrally with a center bearing member welded thereon and with side bearings welded to the top intermediate the center bearing member and the ends of the compression member; a tension bar spaced beneath the compression member and having an intermediate horizontal portion and upwardly inclining straight end portions terminating at the ends and in the horizontal plane of the compression member and welded thereto; and a brace member on each side of the transverse median line of the bolster welded on the tension bar and to the bottom of the compression member beneath the center bearing member and beneath the respective side bearing.

7. In a fabricated truss type truck bolster, the combination of a flanged sheet metal top compression member, extending in a horizontal plane from end to end, provided with a center bearing member welded thereon and with side bearings welded to the top intermediate the center bearing member and the ends of the compression member; a tension bar, spaced beneath the compression member, provided with an intermediate horizontal portion, extending to points beyond the vertical planes of the opposite sides of the center bearing member, and with upwardly inclining straight end portions arranged in angular contact with the ends of the compression member and welded thereto; box-like end members provided with inwardly declining tension bar overlapping portions welded to the ends of the tension bar and said end members welded to the ends of the compression member and extending beyond the ends of the compression member in the horizontal plane thereof, the sides of said end members having laterally disposed spaced lugs for engaging the bolster opening columns of the side frame.

8. In a truss type truck bolster of prefabricated elements integrally united by welding, a compression member extending in a horizontal plane from end to end provided with a center bearing and with side bearings intermediate the center bearing and the ends; a tension bar arranged beneath the compression member and provided with end portions inclining upwardly into contact with the ends of the compression member at an angularity in excess of fifteen degrees, with the ends of the compression member and bar welded together; a pair of V-shaped brace members whose diverging upper ends are secured to the compression member beneath the center bearing and the respective side bearings while the lower ends are secured to the tension bar at points intermediate the vertical planes of the center bearing and the respective side bearings; and end members whose tops are adapted to receive the top portion at the ends of the compression member and provided with downwardly sloping tension bar end supporting portions.
